UNITED STATES PATENT OFFICE.

WILLIAM JOSEPH McDONALD, OF HUNTINGTON, WEST VIRGINIA, ASSIGNOR TO AMERICAN CAR AND FOUNDRY COMPANY, OF ST. LOUIS, MISSOURI, A CORPORATION OF NEW JERSEY.

OILER WITH CAST DUCTILE CASINGS.

1,244,753.

Specification of Letters Patent. Patented Oct. 30, 1917.

Application filed July 25, 1916. Serial No. 111,179.

To all whom it may concern:

Be it known that I, WILLIAM JOSEPH McDONALD, residing at Huntington, Huntington county, State of West Virginia, and being a citizen of the United States, have invented certain new and useful Improvements in Oilers with Cast Ductile Casings, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art. In said drawings:

Figure 1 is a vertical sectional view of a wheel containing an oil reservoir and to which my improved oiler is applied, this being but one of its many possible applications;

Fig. 2 is a longitudinal sectional view of the casting of ductile material in which the immovable parts of the oiler are integrally incorporated;

Fig. 3 is a similar view, showing the valve elements combined with the casing, the integral spring seat and valve guide forming projections of the casing having been bent to a position retaining the valve elements.

Fig. 4 is an elevation of the inlet end of the oiler; and

Fig. 5 is an elevation of the egress port end of the oiler.

It is a purpose of my invention to provide an oiler which may be constructed of but a few simple parts, most of which are standard commodities, easily obtainable in the open market.

It is also intended that the oiler shall have a casing of novel construction which shall be given a preliminary form to permit the insertion of valve elements, the initial form being afterward altered to reliably retain said valve elements. The casing is to be so formed of ductile material, preferably cast, that it will comprise, in its first condition a main barrel portion, serving as a housing for movable valve elements, and also spaced longitudinal extensions pro-

jecting from and aligned with the shell of the barrel portion at one of the annular edges thereof.

It is also proposed to produce the oiler casing in a single piece which shall be provided with means for suitably interlocking the oiler with a portion of a device to be lubricated. A portion of the oiler is to be so constructed that it will coöperate with a suitable tool whereby the insertion of the oiler into the device to be lubricated can easily be accomplished. A suitable inlet port for lubricant is to be provided, preferably in the tool coöoperating portion of the oiler, and the previously mentioned longitudinal extensions from the barrel portion are adapted to be arranged so that they not only coöperate to act as a spring seat and valve guide, but produce a series of lubricant egress ports at the inner end of the oiler. In consequence of the unitary character of the barrel and interlocking portions, the tool-receiving head, the valve seat and the longitudinal extensions, which latter are subject to rearrangement to admit valve elements and at other times to form a combined spring seat and valve guide, together with the ductile character of the casting comprising these elements, permits a very inexpensive, but thoroughly reliable, oiler to be produced.

Such other advantages as appear herein-after are, of course, to be regarded as coming within the scope of this invention.

Referring to the parts, 1 represents the unitary casing of my improved oiler which may be of any suitable ductile material, but which, it has been found in practice, may be advantageously constructed as a malleable iron casting. Casing 1 comprises a main barrel portion 2 containing a valve element 3 beyond which, at one end, project extensions 4 which may, as shown, be actual continuations of the wall of the barrel portion 2 and have the same longitudinal disposition as that wall. Extensions 4 are separated by spaces which partake of the form of notches 5 so that each individual extension 4 is independent of the others when it projects longitudinally from the main barrel portion 2. Intermediate the ends of the ductile casing 1 is a screw threaded portion 6 of greater diameter than the barrel portion 2, and this is true of it with

respect to the outer polygonal end or head 7 of the casing. By reason of the greater diameter of the screw threaded portion, the oiler, which has been shown in Fig. 1 to be applied to the hub of a mine car wheel A, may be adjusted farther inwardly than it could if the head portion 7 had a greater transverse dimension than the diameter of the threaded portion 6. In some devices in which the oiler is capable of being installed, this more extensive longitudinal adjustment of it will be of a material advantage. Tool-receiving head 7 is provided with an inlet port 8 which swells inwardly from an outer large mouth to a considerably reduced valve opening. Because of its curvature, the nozzle of any oil can inserted in the mouth of port 8 will be immediately directed to the inner valve opening without any care on the part of the person supplying lubricant to the oiler.

Directly back of port 8 the metal of casing 1 forms a valve seat 9 which is more or less of a spheric concavity, its greatest diameter being coincident with that of the valve element chamber 3.

In the manufacture of the oiler the malleable casting is first produced in the form illustrated in Fig. 2, and when the longitudinal projections 4 from the barrel portion 2 are in the positions illustrated in that figure, there is a single opening at the inner end of the oiler for the insertion of a valve 10, provided with a stem 11 and a valve actuating spring 12. After the insertion of these valve elements, the oiler may be brought into its completed form by bending the ductile extensions 4 from the positions they occupy in Fig. 2 to those they occupy in Figs. 1, 3 and 5, this requiring but a single and simple operation. Because of the ductility of the metal there is no likelihood of the breakage of extensions 4, but there is enough inherent rigidity in the casting so that extensions 4 will remain in the positions they are placed in.

After being bent as shown in Fig. 3, the extensions 4 reliably retain the valve elements and form a novel seat for the valve spring 12, as best seen in Fig. 5. Extensions 4 originally were parallel with the axis of the casing 1, but in Fig. 5 they are seen to be radially disposed thereto and to the stem 11 of valve 10. The ends of the extensions 4 now also coöperate to form a guide for stem 11 of valve 10 through which said stem may reciprocate. After valve 10 has been pushed inwardly for the admission of lubricant, it will be returned to its normal position upon the withdrawal of the nozzle of the lubricant-replenishing receptacle, and in view of its spherical head and the concave valve seat 9, valve 10 will be automatically self-centered. Moreover, due to the annular spacing of the individual ex-

tensions 4, egress lubricant ports 13 are present which are annularly arranged between extensions 4, intermediate the valve stem 11 and the wall of the barrel portion 2 of the ductile casing 1.

The oiler is susceptible of application to many varied devices requiring lubrication and may be applied by being inserted until its screw threaded portion 6 engages female threads in an aperture provided to receive it, after which it may be screwed farther into and out of the device to be lubricated by the continued turning of the barrel. When there is no reason for doing otherwise, it may be screwed into the device to be lubricated to the extent shown in Fig. 1, but where it is found necessary to carry the lubricant egress ports beyond a certain point, the oiler may be further screwed in because of the inner diameter of the threads 6 being coincident with, but slightly greater, than the larger diameter of the polygonal head 7.

What I claim is:

1. In a lubricating device, a single member formed as a casting and comprising a barrel portion, the wall of which is thicker intermediate its ends than at said ends thereby forming a valve seat intermediate the ends of said barrel portion, having a non-circular outer end portion adapted to receive a tool and terminating at its opposite end in spaced longitudinal extensions adapted to be bent inwardly to serve as a combined spring seat and valve-stem-guide in combination with a valve and valve seating spring.

2. In a lubricating device adapted for attachment to wheels, an integral cast barrel portion provided at one end with a non-circular tool-receiving portion, at its opposite end with integral ductile longitudinal spaced extensions adapted to be folded inwardly to serve as a valve-stem-guide and spring-retaining means, the wall of said barrel portion being thickened intermediate its ends thereby forming a reinforced valve seat and the barrel being provided with a screw thread exterior to, but in proximity to, said valve seat, a valve and a valve-spring within said barrel.

3. In combination in an oiler, a unitary casting of ductile material comprising a barrel portion, a valve seat fashioned therein, and integral extensions projecting longitudinally from said barrel portion, a valve having a stem and a valve spring, said extensions being arranged to form a single opening for the insertion of said valve and spring in said barrel portion and being adapted to be bent to form a seat for the spring a guide for the valve stem and to convert said single opening into a plurality of ports in the inner end of said barrel portion.

4. In combination in an oiler, a barrel portion containing a valve-element chamber and circumferentially spaced longitudinal extensions from an undivided part of said barrel portion, all being parts of a unitary malleable casting, and valve elements including a spring, said extensions being adapted to be bent at their juncture with said undivided barrel part to form a spring seat, a valve guide and lubricant ports in an end of said casing. 5
5. In combination in an oiler, a barrel portion having a rigid terminal and containing a valve-element chamber fashioned to include an automatic centering valve seat and spaced longitudinal extensions from said rigid terminal of said barrel portion, all being parts of a unitary ductile casing, a valve spring and a valve coöperating with said valve seat to be self-centering, said extensions being adapted to be bent to form an apertured spring seat and a valve guide. 10
6. In combination in an oiler, an in-expansible barrel portion, an automatic centering valve seat therein, a portion forming an inlet port shaped to automatically direct the nozzle of a replenishing receptacle and a plurality of bendable individual extensions from said barrel portion bendable to change the directions of substantially their entire lengths, all being parts of a unitary ductile casing, a valve shaped to coöperate with said valve seat to be self-centering and a valve spring, said extensions normally forming a valve guide and spring seat through which lubricant is adapted to flow. 15
7. In combination in an oiler, a chamber-forming barrel portion provided with an inlet port and fashioned to have a valve seat and separated extensions of the wall of said barrel portion beginning at one terminal of
- the chamber therein, all being parts of a unitary ductile casing, a valve provided with a stem and a spring normally pressing 45 said valve against said seat, said extensions primarily extending parallel to the axis of the valve stem and being adapted to be bent to radiate therefrom to form a spring seat and valve stem guide through which lubricant may flow. 50
8. In combination in an oiler, a barrel portion adapted to be inserted in a device to be lubricated having a head for the reception of a tool for accomplishing such insertion provided with an inlet port, a portion adapted to interlock with the device to be lubricated, having a greater transverse dimension than that of said barrel portion and head, an internal valve seat and extensions from said barrel portion, all being parts of a unitary ductile casing, a valve and valve spring, said extensions being primarily disassociated but being adapted to be bent substantially throughout their 60 lengths to form a spring seat, valve guide and egress lubricant ports. 65
9. In combination in an oiler, a barrel portion having a valve seat therein, a valve and a spring therefor, each of less transverse dimension than the interior of said barrel portion, said barrel portion having prongs extending from the latter adapted to continuously contact with said valve, said prongs forming a spring seat and retaining 70 said valve and spring in said barrel portion but adapted to be bent to permit the withdrawal of said valve and spring. 75

In witness whereof I have hereunto set my hand in the presence of two witnesses.

WILLIAM JOSEPH McDONALD.

Copies of this patent may be obtained for five cents each, by addressing the "Commissioner of Patents, Washington, D. C."

It is hereby certified that in Letters Patent No. 1,244,753, granted October 30, 1917, upon the application of William Joseph McDonald, of Huntington, West Virginia, for an improvement in "Oilers with Cast Ductile Casings," an error appears in the printed specification requiring correction as follows: Page 3, line 18, claim 5, for the words "ductile casing" read *malleable casting*; and that the said Letters Patent should be read with this correction therein that the same may conform to the record of the case in the Patent Office.

Signed and sealed this 29th day of January, A. D., 1918.
